UNITED STATES PATENT OFFICE.

JOSEPH J. JANCA, OF ST. LOUIS, MISSOURI, ASSIGNOR TO THE EMERSON ELECTRIC MFG. CO., OF ST. LOUIS, MISSOURI, A CORPORATION OF MISSOURI.

ELECTRIC MOTOR.

Application filed March 31, 1927. Serial No. 179,755.

This invention relates to electric motors, and more particularly to a combination short circuiting and brush lifting mechanism.

An object of the invention is to provide a short circuiting unit adapted to be operated by centrifugal force, in combination with brush lifting mechanism conjointly operated with a short circuiting mechanism.

Additional objects and advantages thereof will be readily apparent from the following detailed description, taken in connection with the accompanying drawing, in which,

Fig. 1 is a longitudinal section.

Fig. 2 is an end elevation, the armature shaft being in section.

Fig. 3 is an elevation showing particularly the arrangement of the brush lifting mechanism.

In the embodiment of the invention illustrated in the drawing, the armature shaft 1 carries a shell 13 supporting a ring 2 on which the commutator segments 3 are clamped. The short circuiting of the armature is effected by actuating a contact disc 25 against the vertical faces of the commutator segments. The contact disc comprises a ring 4 having a plurality of spaced fingers 5 having their outer portions inclined toward the commutator segments (Fig. 1).

The ring 4 is loosely retained on one end of a sleeve 6 by a ring 7. At the opposite end of the sleeve 6 is a ring 8 and a coil spring 9 around the sleeve 6 is between the ring 8 and the ring 7. The inner end of the sleeve 6 is flanged, so that the ring 7 is prevented from moving toward the commutator faces when the sleeve 6 is in its outer adjustment, that is to say, when the motor is at rest. The forward end of the sleeve 6 has an inwardly turned flange 10, against which one end of an expansion spring 11 is seated, the other end of said spring 11 bearing against the base of a recess 12 in a member 13 carried by the armature shaft and on which the ring 2 is mounted.

A ring 14 around the armature shaft is spaced inwardly from the flange 10 at the end of the sleeve 6. Another coil expansion spring 15 around the armature shaft bears against the ring 14 at one end and seats in the recess 12 of the member 13 at the other end. The ring 14 has forwardly projecting arms 16 that extend through openings in the flange 10 and in the ring 8, and also through a ring portion 17 of a spider having a plu-

rality of arms 18. A second spider comprising a ring portion 19 and arms 20 is attached to a member 21 on the armature shaft. Each arm 18 is formed with a shoulder 22 and the arms 20 are arranged in spaced pairs so that the arms 18 project between them. The arms 20 are inwardly inclined and rollers 23 having reduced portions 24 are mounted between the arms 18 and 20, the reduced portions of the rollers bearing against the shoulder 22 of the arms 18 and the rollers contacting with the inner faces of the arms 20.

When the armature shaft is rotated, the rollers move centrifugally and, as the arms 20 are fixed to the armature shaft, the spider comprising the ring 17 and the arms 18 is actuated inwardly along the armature shaft. This action results in pressure on the ring 8, which is resiliently transferred to the ring 7 and, at the same time, the sleeve 6 is moved inwardly against the tendency of the spring 11, so that both the ring 7 and the ring 4 are moved toward the commutator segments 3, causing the fingers 5 to contact with said segments, thereby short circuiting the commutator. As a result of the continued inward movement of the ring 8, and thereby the inward movement of the sleeve 6, the flange 10 of the sleeve is caused to contact with the ring 14, thereby moving the arms 16 inwardly.

The outer ends of the arms 16 are connected to a ring 25 mounted to slide on the member 21. The brushes 26 are movably supported in brush supports 27. The supports 27 are carried by a ring 28 fixed to the end plate of the motor. The brush supports have forwardly extending arms 29, upon each of which is pivoted a bell crank lever 30 having an extension 31, the forward end of which is bifurcated and is pivotally connected by a pin 32 with the brushes. Springs 33 are connected at one end with the respective arms 29 and at the opposite end with the respective bell crank levers 30. These springs tend to actuate the extensions 31 of the bell crank levers and thereby move the brushes from the commutator segments. Each of the bell crank levers has an inclined tail piece 34 which contacts with the ring 25.

After the sleeve 6 has moved inwardly sufficiently to contact with the ring 14, the arms 16 are drawn inwardly against the tendency of the spring 15, thereby permitting the bell crank levers 30 to be moved by the action of

the springs 33, thereby raising the brushes out of contact with the commutator segments. When the motor is at rest, the pressure on the ring 25, by action of the spring 15 pressing the ring 14 and its arms 16 outwardly, causes the brushes to be actuated into contact position. The brushes remain in contact until the machine has functioned to contact the fingers 5 with the front faces of the 10 commutator segments. The brushes are then moved from contact position in the manner described.

When the speed of rotation of the armature shaft is reduced, the rollers 23 return to the 15 position shown in Fig. 1, at which time the contact fingers 5 are out of contact with the commutator segments 3, and the brushes are in contact with the commutator segments.

I am aware that the invention may be 20 modified in numerous particulars without departure from the spirit and scope of the invention, but what I claim and desire to secure by Letters Patent is:—

1. A short circuiting mechanism comprising 25 a contact member movable to make and break contact with commutator segments, a movable support for said contact member, a spring actuating said support to position in which said contact member is out of contact 30 with the commutator segments, a fixed member, a series of rollers operating against said member for centrifugal movements, and elastic means operated by said rollers for moving said support to position in which said contact member contacts with the commutator segments.

2. A short circuiting mechanism comprising 40 a contact member movable to and from contact with contact segments, a movable support for said member, a spring actuating said support to position in which said member is out of contact with the commutator segments, a fixed member inclined toward said support, an element for moving said 45 support to position in which said contact member contacts with the commutator segments, a spring holding said contact member and said element in spaced relationship, and a series of rollers operable centrifugally 50 against said inclined member to actuate said element to cause said element to move said support to position in which said contact member contacts with the commutator segments.

55 3. A short circuiting mechanism comprising a contact member movable to and from contact with commutator segments, a movable support for said contact member, a spring yieldingly holding said support in position in which said contact member is out 60 of contact with the commutator segments, a fixed member inclined toward said support, actuating rollers arranged to operate centrifugally against said fixed member, and 65 elastic means controlled by said actuating

rollers to move said support to position in which said contact member is in contact with the commutator segments.

4. A short circuiting mechanism comprising 70 a contact member movable to make and break contact with commutator segments, a movable support for said contact member, a spring actuating said support to position in which said contact member is out of contact 75 with the commutator segments, a fixed member, a series of rollers operating against said member for centrifugal movements, means operated by said rollers for moving said support to position in which said contact member contacts with the commutator segments, 80 brushes movable into and out of contact with the commutator segments, and means for moving said brushes out of contact with the commutator segments when said contact member moves into contact with the commutator segments.

5. In an electric motor, commutator segments, brushes movable into and out of contact with said segments, a lever pivotally connected with each of said brushes for moving 90 the brushes out of contact with said segments, a spring for actuating each of said levers in a direction to move said brushes out of contact with said segments, an element holding 95 said levers in position to hold said brushes in contact with said segments, relatively rigid arms inclining toward said segments, and centrifugal devices guided by said arms for moving said element to position to permit 100 said springs to move said brushes out of contact with said segments.

6. In an electric motor, commutator segments, brushes movable into and out of contact with said segments, a lever pivotally connected with each of said brushes for moving 105 the brushes out of contact with said segments, a spring for actuating each of said levers in a direction to move said brushes out of contact with said segments, an element holding 110 said levers in position to hold said brushes in contact with said segments, relatively rigid arms inclining toward said segments, centrifugal devices guided by said arms for moving said element to position to permit 115 said springs to move said brushes out of contact with said segments, and means for moving said element to actuate said levers to position in which said brushes contact with said segments.

7. In an electric motor, the combination 120 of a rotary armature shaft, commutator segments supported about said shaft, brush guides and brushes movable in said guides into and out of contact with said segments, of a lever pivotally connected with each of said brushes, springs for actuating said levers to move said brushes from contact with said segments, a device supported by said shaft 125 for holding said levers in position in which said brushes contact with said segments, and 130

said segments, a spring for actuating said member, centrifugal elements for causing said spring to move said contact member into contact with said segments, means for moving said brushes out of contact with said segments and actuators for moving said contact member out of contact with said segments and said brushes into contact with said segments.

16. In an electric motor, the combination of a rotary armature shaft, commutator segments having vertical and horizontal faces, a contact ring mounted to move longitudinally of the shaft to make contact with the vertical faces of said commutator segments, brushes movable radially of said shaft to make contact with said horizontal faces of said commutator segments, resilient means normally holding said brushes in contact with said commutator segments and said ring out of contact with said commutator segments, and centrifugal means operating in opposition to said resilient means operated upon the rotation of said armature shaft to cause said

ring to make contact with said commutator segments and to release said brushes from said commutator segments, including oppositely disposed abutment members, one of which is fast on the shaft and the other of which is loose thereon, rollers interposed therebetween, and connections between the brushes and said contact ring.

17. In an electric motor, the combination with an armature shaft, of an armature carried thereby having commutator segments, a contact ring movable longitudinally of the shaft, a spring operatively connected with said contact ring, commutator brushes, a second spring connected with said commutator brushes and normally holding the same in contact with said commutator segments, and centrifugal devices operating in opposition to said springs for releasing the tension thereon whereby the contact ring makes contact with said commutator segments and as an incident thereto the brushes are released from contact with said commutator segments.

JOSEPH J. JANCA.
